[57] CLAIM

The ornamental design for a combined dental floss holder and tooth pick, as shown and described.

DESCRIPTION

FIG. 1 is a front elevation of a combined dental floss holder and tooth pick, the opposite rear side being identical and a mirror image of the front;

FIG. 2 is a side elevation thereof as seen from the left of FIG. 1; and

FIG. 3 is a plan view as seen from the bottom of FIG. 1.
